CLAIM

(22) Filed: **Jan. 22, 2020**

The ornamental design for a snap-lock construction toy beam connector, as shown and described.

(51) **LOC (13) Cl. 21-01**

DESCRIPTION

(52) **U.S. Cl.**

FIG 1 illustrates a front, top, and right side perspective view of a snap-lock construction toy beam connector according to the present invention.

USPC **D21/492; D21/504**

FIG. 2 illustrates a rear, bottom, and left side perspective view of the snap-lock construction toy beam connector of FIG. 1.

(58) **Field of Classification Search**

FIG. 3 illustrates a front elevation view of the snap-lock construction toy beam connector of FIG. 1. FIG. 4 illustrates a rear elevation view of the snap-lock construction toy beam connector of FIG. 1.

USPC D21/484, 485, 489, 490, 492, 493, 494,
D21/495, 500, 501, 502, 503, 504
CPC A63H 33/00; A63H 33/04; A63H 33/06;
A63H 33/062; A63H 33/08; A63H
33/084; A63H 33/088; A63H 33/101;
A63H 33/108; A63H 33/12

FIG. 5 illustrates a left side elevation view of the snap-lock construction toy beam connector of FIG. 1.

See application file for complete search history.

FIG. 6 illustrates a right side elevation view of the snap-lock construction toy beam connector of FIG. 1.

(56) **References Cited**

FIG. 7 illustrates a top elevation view of the snap-lock construction toy beam connector of FIG. 1; and,

U.S. PATENT DOCUMENTS

FIG. 8 illustrates a bottom elevation view of the snap-lock construction toy beam connector of FIG. 1.
